UNITED STATES PATENT OFFICE

ALBERT C. FISCHER, OF CHICAGO, ILLINOIS, ASSIGNOR TO THE PHILIP CAREY MANUFACTURING COMPANY, A CORPORATION OF OHIO

ASPHALT EXPANSION JOINT

Application filed July 28, 1922. Serial No. 578,177.

This invention relates to an improvement in asphaltic expansion joints for concrete pavements. Heretofore it has been customary to use dusting material upon the sides of asphalt expansion joints to prevent the sides sticking to one another in packing. Later it was found advantageous to coat one of the sides with a layer of saturated felt squeezed dry. This was followed by coating the sides with open meshed burlap, and was later followed by using felt sides on both sides of the asphalt materials, the purpose being to make the joint easier to handle on the part of the contractor.

15 Talc, bone dust and other substances used as dusting materials soon become penetrated by the asphaltic material, and, therefore, do not bind with the concrete in the road when poured against the sides. Likewise the saturated felt by reason of its waterproof nature does not permit of adhesion to the concrete sides when the moist batch of concrete is poured up against it, and consequently there is no true adhesion.

25 In the accompanying drawings:—

Fig. 1 is a section of expansion joint strip embodying my invention; and

Fig. 2 is a section of paving in which the novel expansion joint strip is inserted.

30 The purpose of this invention is to furnish dusting materials and apply them on the sides of the asphaltic body in such a manner that they not only prevent the joints from adhering to each other in the crates, but by 35 using a binding means the dusting particles are united as when dusted upon the asphaltic body, and are constituted of materials which readily unite with the concrete mass, so that when the concrete batch is poured up against 40 the sides of the expansion joint it becomes one cohesive whole, and the particles on the side become a part of the concrete mass.

The proper method of accomplishing this result is by coating the sides of the asphaltic 45 mass with a layer of adhesive material. It may be performed in various ways. For instance, a layer of silicate of soda in the nature of a very thin film 3 may be prepared and coated over the sides of the asphaltic body 50 2, or other substances may be mixed, such as,

silicate of soda and calcium chloride, which will furnish a waterproof substance as a binder. Likewise, a very high melting point asphalt may be used as the binding means, which cools quickly when heat is removed. 55 Into this binding material is dusted preferably such substances 4 as short asbestos fibre, or if the asbestos fibre is not economically suitable, a mica flake may be dusted upon the sides, which upon being dusted are 60 pressed into the binder so that some of the binder presses between the particles of dusting material, but not sufficiently to ooze to the surface, thus endangering adhesion of the joints when packed in the crate. This automatically creates a film adhering to the sides of the asphaltic mass, which prevents adhesion of the joints when packed in crates, and likewise a film which when a concrete mixture is poured up against it readily sets 70 with the concrete, becoming a part of the concrete slabs 5, and by reason of its previous adhesion to the asphaltic slab becoming one uniform mass.

75 I claim:

1. An expansion joint for concrete pavements, consisting of a body containing a substantial proportion of bituminous substance, having a form which adapts it to serve as a division wall in molding concrete pavement, 80 and having upon its surface through which it receives poured concrete, a binding material consisting of subdivided fibrous material adhered to the body portion by a cement that is adhesive to it as well as to the bituminous material of the body, but leaving uncovered by the bituminous substances and exposed an outer surface which enters into bond with the water mixed concrete when poured 85 against it.

2. A bituminous expansion joint having coated upon its sides a binding material adhesive to bituminous substance and having dusted upon said binding material a bonding material in subdivided form, which is adhesive both as to the binding material and water mixed concrete when poured against it.

3. A bituminous expansion joint having coated upon its sides a binding material comprising sodium silicate adhesive to bitumi-

nous substance and having dusted upon said binding material a bonding material adhesive both as to the binding material and water mixed concrete when poured against it; said bonding material consisting of a fibrous substance distributed upon the binding material while the substance is in subdivided form, thereby causing the fibers to be intimately interwoven.

10 4. An article of manufacture composed of a body of bituminous material having a coating film on its surface which is normally non-adhesive but capable of becoming adhesive in the presence of water, and granular material partially embedded in the coating film to provide projecting uncoated areas.

15 5. An article of manufacture composed of a body of bituminous material having a coating film of sodium silicate.

20 6. An expansion joint composed of a body of bituminous material having an adhesive coating on its surface, and granular material partially embedded in said coating to provide a rough uncoated surface area adapted to bond with adjacent plastic material.

25 7. A paving structure comprising concrete slabs and interposed expansion joint strips, said strips being composed of a bituminous slab coated upon its sides, with a binding material adhesive to a bituminous substance and having dusted upon said binding material a bonding material in subdivided form, which is adhesive both as to the binding material and adjacent water-mixed concrete.

30 8. A paving structure comprising concrete slabs and interposed expansion joint strips, said strips composed of a body of bituminous material having an adhesive coating on its surface, and granular material partially embedded in said coating to provide a rough uncoated surface area adapted to bond with adjacent plastic material.

35 Signed at Chicago, Illinois, this 24th day of July, A. D. 1922.

ALBERT C. FISCHER.
